COLLAPSIBLE SUPPORT FOR DIFFUSION BATTERY CELL CHAINS

Filed Nov. 27, 1926

3 Sheets-Sheet 2

A technical drawing of a circular truss structure, likely a wheel or a large circular frame. The structure is divided into sectors by radial and diagonal members. Key features include:

- Vertical Members:** A central vertical member labeled 'P' and 'R' at its base, and a vertical member on the right labeled 'E'.
- Diagonal Members:** Diagonal members are labeled with angles: '43°' (top-left, top-right, bottom-left, bottom-right), '43' (top-left, top-right, bottom-left, bottom-right), '20' (center-left, center-right), '22' (center-right), and '42' (center-left, center-right).
- Horizontal Members:** Horizontal members are labeled with letters: 'E' (top-left, top-right), 'K' (top-left, top-right, center-left, center-right), 'L' (bottom-left, bottom-right), 'F' (center-left, center-right), and 'R' (bottom-left).
- Other Labels:** The label 'FIG. 2.' is written in the top-left corner of the drawing area.

UNITED STATES PATENT OFFICE.

EDWIN H. CROFOOT, OF MASON CITY, IOWA.

COLLAPSIBLE SUPPORT FOR DIFFUSION-BATTERY-CELL CHAINS.

Application filed November 27, 1926. Serial No. 151,065.

This invention relates to improvements in collapsible supports for diffusion-battery-cell chains, pertaining more particularly to a collapsible support adapted for use in battery cells, such as are used in the process and apparatus for the extraction of sugar from beets, or the like.

The present apparatus is particularly adapted for use in connection with a diffusion battery or cell, such as is used in beet sugar factories but the invention is not limited to this use, as the principles of the invention can be utilized for other purposes, as will readily appear in the following description.

In broad terms the invention comprises a collapsible support mounted within a diffusion battery or cell and provided with means operated externally of the cell for causing the support to assume its extended position, or permit the support to be collapsed when desired.

The present invention has a number of objects and accomplishes a number of improved results. The objects of the invention are listed below and the manner in which they are accomplished will be pointed out in the following description.

One object of the invention is to provide an increased capacity for the battery or cell.

Another object of the invention is to accomplish the removal of more sugar from the matter being worked upon in the cells.

A further object of the invention is to provide a support for the matter in the cell and to construct the support in a manner whereby the support can be collapsed and thus permit easy and rapid removal of the matter from the cell.

A further object of the invention is to provide means for agitating the matter or pulp being worked upon in the cell, so as to distribute the pulp therein uniformly whereby the sugar can be washed and extracted from the pulp with the use of less water and in a shorter time.

Another object of the invention is to increase the production of a battery cell and, consequently, the plant in which the cell is installed, and to effect a very material saving of coal, or other heating medium, used by the plant.

Another object of the invention is the provision of a collapsible support for chains in a battery or cell, the operation of which is controlled by power at the will of the

operator, which will permit the rapid and easy ejection of the pulp from the cell and will require the use of less wash-water to bring about the ejection.

A still further object of the invention is to hold the material in the battery or cell in suspension and thereby increase the rapidity of the dilution and very materially reduce the amount of dilution water required to effect the extraction.

Other objects, novel features of construction and improved results of the invention will be pointed out in the following description and set forth in the accompanying drawings.

In the accompanying drawings:—

Figure 1 is a view of the side elevation of a battery or cell having mounted therein a support made in accordance with the invention.

Fig. 2 is a top plan view of Figure 1.

Fig. 3 is a sectional view showing the manner in which the support arms are attached to the vertical support column.

Fig. 4 is an enlarged view in vertical section of the upper end of the support, the parts being shown in the positions they assume when the support is collapsed.

A battery cell A, is used in connection with the invention. This battery cell is ordinarily supported in some suitable manner below a flooring or platform 5, and is provided at its upper end with a door 6, and at its lower end with a downwardly swinging door 7. The cell, as appears in the drawings, is ordinarily a cylindrical drum being set vertically, the upper and lower ends of the drum being funnel-shaped, as at 8, adjacent the upper and lower doors. The beet cossettes, or other material from which the sugar is to be extracted, is placed in the cell through the upper door 6, and ejected from the cell through the bottom door or trap 7. Water under pressure is delivered to the upper end of the cell from a suitable source of supply through the pipe 9, and after passing through the material in the cell leaves the lower end of the cell through the pipe 10. The lower funnel-shaped end of the cell is provided with a screen 11, supported in separated relation from the cell sides by suitable spaces 12. This screen also extends over the inner surface or face of the drop door or gate 7 and prevents the clogging of the outlet pipe 10.

The construction, heretofore described, is

one that is common and well-known in the art.

The present invention comprises, in general terms, a vertical support column B, a base-supporting bar C, a cylinder D, a series of supporting arms E, F, G, H and J, a series of supporting and lifting chains K, L and M, and a piston rod N, having at one end a piston O, and at its opposite end a spider P.

In describing the invention in greater detail, it will be seen that the supporting base or bars C have their outer ends suitably fastened as at 13 to the cell walls, while their inner ends are attached as at 14 to the outwardly extending portions 15 of the cylinder D. The lower end of the cylinder is closed by a suitable plug or fitting 16, provided centrally with an opening or channel 17, to which is connected the pipe 18 for carrying hydraulic pressure.

The piston O is mounted for reciprocation in the cylinder D and the piston rod N extends upwardly through the cylinder top 19, to a point near the top of the cell, carrying on its upper end the spider or yoke P, which is held in place by bolts 20 or the like. The piston rod is adapted to move in the hollow vertical supporting column B, the lower end 21 of which is supported in the cylinder top 19, making therewith a water-tight connection. The upper end of the column B is closed by a cap 22, having threaded connection as at 23, with a sleeve 24, which in turn is threaded upon the upper end of the column 25. The cap 22 is provided with an inwardly extending peripheral flange or shoulder 26, between which and the upper end of the column is interposed a sliding collar 27, having a lower beveled edge 28, adapted to engage suitable packing 29 supported on the upper end of the column. It will be clearly seen that by tightening the cap 22 downwardly upon the sleeve 24, a water-tight closure is provided for the upper end of the column.

To prevent the downward movement of the yoke P, upon the piston rod N, this rod is reduced in size as at 30, adjacent its upper end so that the yoke rests upon the shoulder 31 of the rod.

At intervals throughout the length of the column B, there are provided collars R. As clearly appears in Fig. 3 of the drawings, these collars are made in semi-circular half portions 32 and 33, being held in clamped position upon the column by reason of the bolts 34. When the collars are in place, they provide four outwardly extending yokes 35, in which are pivotally supported by bolts 36 or the like, the reduced ends 37 of the supporting arms E, F, G and H. In their preferable form, these supporting arms are made of hollow tubing, and the ends 37 are extensions which are attached

internally of the tubes by suitable fastening means, such as appears at 38.

From the foregoing it will be understood that each collar R carried four supporting arms arranged at angles of 90° in respect to one another. Attention is directed to the fact that the collars are so positioned upon the column that the supporting arms carried by the top collar will not be directly above the supporting arms carried by the second collar. The supporting arms carried by the third collar will be directly beneath those carried by the first collar, while the supporting arms of the fourth collar will be directly beneath those carried by the second collar. In this manner a network of the supporting arms is provided in the cell.

The lower-most collar R, which carries the supporting arms J, is mounted upon the cylinder plug 16, being held against slipping off by a suitable nut 39. The supporting arms J are, of course, below the bars C.

The yoke P comprises four outwardly extending arms 40, and are provided in their ends with suitable connections 41, with downwardly extending chains K, which are connected as at 43', with the four supporting arms E. The outer ends of the supporting arms E, are in turn connected by suitable chains L, with the supporting arms H, while the outer end of the supporting arms G have connection with the supporting arms J, through the medium of the chains M. Each supporting arm is additionally provided with a chain 42, which hangs in an arc having one of its ends connected to the end of the supporting arm, while its opposite end is attached to the collar R. The chains 42 of the arms E are additionally provided with downwardly extending chain connections 43, which are attached to the supporting arms F. The outer ends of the supporting arms F are connected to the supporting arms G, through the medium of chains 44.

By reason of the chains K, L and M, chains 42, 43 and 44, it will be seen that as the piston rod N is raised, the supporting arms E, F, G, H and J will be raised and will finally assume the horizontal positions shown in Figs. 1 and 2, whereas when the piston rod is in its lowermost position, as appears in Fig. 4, the supporting arms will hang parallel the supporting column B.

To effect the raising and lowering of the piston, and consequently the piston rod N and yoke P, the pressure pipe 18 is carried outwardly from the cell to a point of suitable hydraulic pressure supply (not shown) and is provided with a three-way cock or valve 45, which in turn is provided with an elongated stem 46, which extends to a point above the flooring 5, where there is provided a handle 47. There is no invention in the three-way valve itself, as it is merely a valve

which in one position will permit the passage of high pressure fluid to the cylinder D; in its second position it stops the admission of fluid, and in its third position continues to stop the admission of fluid and additionally permits the escape of fluid from the cylinder out of the outlet pipe 48.

It will, therefore, be seen that there is provided in the cell a collapsible support for 10 the chains which is controlled at the will of the operator by the mere turning of the control handle 47.

It will be readily seen that the supporting arms and the net-work of chains will suspend to a large degree the material in the cell and prevent its packing upon the cell screen 11. The invention is not limited to the particular arrangement of the chains shown and described, as additional chains 20 can be added for supporting the material without departing from the spirit of the invention.

It has been found that the closer the material is packed into the cell without sagging down, the better the extraction. As a cell ordinarily holds about five tons of material, it will be readily realized the importance of suspending the material, so that the water can reach all parts of it and, therefore, effect a much better extraction than would be possible were the whole weight rested upon the cell bottom. Furthermore, with the entire weight of the mass upon the cell bottom and screens, it would probably 30 pack so tight that the water could not be forced readily through the mass which, in addition to meaning poor extraction would also stop up to a large degree the escape of water through the outlet pipe 10.

40 After the extraction process, which takes place within the tightly closed cell, no opportunity being possible to examine the action within or knowing how thoroughly it has been done, the top and bottom traps and 45 doors 6 and 7 are opened, the water supplied through the pipe 9 having first been cut off.

The ejection of the pulp or matter now takes place. With cells now known and used, it has been found that the material 50 in the cell has become clogged and that a great deal of work is required to dislodge it and start its movement through the bottom door opening 7. That this is true will be readily realized when it is considered 55 that there is in the cell approximately five tons of wet mass, approximately ten feet deep, and that this mass is stuck fast in the cell. It has been found that oftentimes this mass moves downwardly with some persuasion, which is assisted by a stream of water under high pressure, which is directed upon the mass through the open upper door 6. In the cells now known, the material is supported, during the extraction process, by 60 stationary chains within the cell and it has

been found that after the bulk of the mass has passed out a great deal of wash-water is required to remove the material which remains clinging to the chains and side walls of the cell. 70

With the present invention these disadvantages are overcome. With the bottom door of the cell open and supporting arms and chains can be dropped which will immediately dislodge the mass and start it 75 downward through the bottom outlet opening. It has been found that practically the entire mass is immediately dislodged and starts downward. The small amount of matter remaining clinging to the chains and 80 side walls will require a very small quantity of wash-water to thoroughly clean them. It is one of the primary functions of this invention to start this drop of the matter or pulp quickly and to urge it along by the 85 movement of the movable supporting arms and thus eliminate a very considerable amount of work, a large volume of wash-water, and considerable time, which in the extraction of sugar is a large item. By 90 reason of the great weight resting on the chains and the supporting arms, it will be readily seen that immediately the pressure beneath the piston O is released that these 95 members will drop immediately. 95

A drain valve 49 is provided for the column B to drain any water from the column which may enter it past the piston. This is desirable for were it not released, this water would become foul after a time. 100

To effect a packing of the materials in the cells, during the loading process, which is very desirable, the arms and supporting chains are occasionally raised and lowered and will insure an effective packing of the 105 cell. The raising and lowering of these arms and chains during the process of extraction which agitate the material and offer all surfaces of the cossette to the dilution or extraction of water, thereby effecting a most 110 rapid and thorough extraction. 110

By reason of the movable features of the device, and the external control making the operation of the device possible while the cell is under pressure, and its material aid 115 in unloading the cell, it will be seen that by uses of multiples of the device in a single cell or a succession of cells, one above the other, with the adaptation of methods for ejecting the pulp after extraction is 120 complete, as well as methods of loading the material in the upper cell, or cells, it is possible and feasible to effect a continuous extraction process which would be highly efficient, economical and rapid. 125

From the foregoing, it will be seen that many advantages accrue through the use of this invention. Due to the effective agitation of the material a greater amount of sugar is obtained in the extraction process. 130

By holding the material in suspension, the extraction process is greatly shortened and the amount of dilution water required to effect extraction is materially reduced. By reason of the unloading aid given by the invention a great amount of time and labor is saved in this step and the volume of wash-water is materially reduced. At the same time the cell is not out of operation for as long a time as has been the case heretofore. The reduction of the amount of dilution water necessary to effect the extraction will effect a very marked reduction in the coal necessary for this step in the process. The cost of coal used in the evaporation or extraction process constitutes a large item as to the cost of obtaining sugar.

Having thus described my invention, what I claim and desire to secure by Letters Patent is:—

1. The combination with the cells of a diffusion battery of supports mounted in said cells, said supports comprising a series of arms, and means to move said arms into and out of supporting positions.
2. The combination with the cells of a diffusion battery of collapsible supports in said cells, and means for moving said supports from collapsed to extended positions.
3. The combination with the cells of a diffusion battery of collapsible supports in said cells, means for moving said supports from collapsed to extended positions, and said operating means controlled externally of the cells.
4. The combination with the cells of a diffusion battery of collapsible supports in said cells, and pressure operated means for moving the supports from collapsed to extended positions.
5. The combination with the cell of a diffusion battery, of a collapsible support in said battery, said support comprising a vertical column and a plurality of supporting members, said supporting members pivotally mounted in respect to said column, and means for swinging said supporting members from collapsed to extended positions.
6. The combination with the cell of a diffusion battery of a collapsible support in said cell, said support comprising a vertical column adapted for reciprocation, a series of supporting arms pivotally mounted in respect to said column, and means for reciprocating said column, whereby the supporting arms are swung from collapsed to extended positions.
7. The combination with the cell of a diffusion battery of a collapsible support in said cell, said support comprising a vertical column having a series of supporting arms pivotally mounted in respect thereto, a vertical reciprocating member in the vertical column and having connection with the supporting arms, supporting chains suspended

from said supporting arms, and means for reciprocating the said movable column, whereby the supporting arms and chains are moved from collapsed to extended positions.

8. The combination with the cell of a diffusion battery of a collapsible support in said cell, said support comprising a hollow vertical column having a series of supporting arms pivotally mounted in respect thereto, each series of arms comprising four arms positioned at angles of 90° in respect to one another, the supporting arms of the alternate series positioned in respect to its adjacent series of supporting arms in a manner whereby none of its supporting arms are directly in line with the supporting arms of the adjacent series, a vertical reciprocating member in the vertical column and having connection with the supporting arms, and means for reciprocating said movable column, whereby the supporting arms are moved from collapsed to extended positions.

9. The combination with the cell of a diffusion battery having an outlet opening in its bottom, of a support in said cell, said support having movable arms adapted to support the material in the cell and to aid the ejection of the material from the cell, and means for moving said supporting and ejecting arms.

10. The combination with the cell of a diffusion battery, of a collapsible support in said cell, said support comprising a vertically movable member and a plurality of supporting members pivotally mounted in respect thereto, a cylinder in said cell, the vertically movable member provided with a piston adapted for reciprocation in said cylinder, means for conveying pressure to said cylinder and permitting the escape of pressure from the cylinder, and means external of the cell for controlling the admission and escape of the pressure.

11. The combination with the cell of a diffusion battery of a member in said cell for supporting, agitating and ejecting the material in the cell, said member having a plurality of movable arms, and means for imparting movement to said arms when desired.

12. The combination with the cell of a diffusion battery of a collapsible support in said cell, said support comprising a vertical column and a plurality of supporting members pivotally mounted in respect thereto, and means for imparting upward and downward movement to said supporting members, whereby said members support, agitate and eject the material in the cell.

13. The combination with the cells of a diffusion battery, of supports mounted in said cells, each of said supports comprising a series of arms, and pressure operated means to move said arms into and out of supporting positions.

14. The combination with a cell of a diffusion battery, of a collapsible support in said battery, said support comprising a vertical column and a plurality of supporting members, said supporting members pivotally mounted in respect to said column, and pressure means for reciprocating said column whereby the supporting arms are moved upwardly and downwardly and swung from collapsed to extended positions.
- 10 15. The combination with a cell of a diffusion battery, of a collapsible support in
- said cell, said support comprising a vertical column adapted for reciprocation, a series of supporting arms pivotally mounted in respect to said column, and pressure means 15 for reciprocating said column whereby the supporting arms are moved upwardly and downwardly and swung from collapsed to extended positions.

In testimony whereof I hereunto affix my 20
signature.

EDWIN H. CROFOOT.
